YARN TWISTING APPARATUS

Chester L. Loveland, Dalton, Pa., assignor to U.S. Textile Machine Company, Scranton, Pa., a corporation of Pennsylvania

Filed Jan. 6, 1966, Ser. No. 519,093

9 Claims. (Cl. 57—119)

ABSTRACT OF THE DISCLOSURE

In a yarn twister combination a yarn guide means having the construction of a bearing and a ring traveller having a yoke assembly attached at its closed end to the traveller and having a freely rotatable grooved roller mounted within the open end.

The present invention relates to yarn twisters and in particular to a ring traveller and yarn guide for use in a twister.

The present invention finds application in a twister in which a bobbin is rotated and the yarn is guided to the bobbin first through a yarn guide coaxial with the bobbin and then through a ring traveller which slides along the inner periphery of a guide ring which surrounds the bobbin.

In the presently known yarn guides, the yarn moves around the inner periphery of a stationary ring in a manner which, after a period of usage, wears the inner surface of the ring away, and eventually causes uneven and improper guiding of the yarn.

In the presently used ring travellers, the yarn is passed through the ring traveller in one or even two right angle bends, causing strain and frictional wear on the yarn and ring traveller, resulting in the weakening of the yarn and eventual wearing away of the surface of the ring traveller.

It is, therefore, a general object of this invention to provide, in a yarn twister, a ring traveller and yarn guide which will substantially reduce the wear on the yarn during the twisting operation.

It is a further object of the present invention to provide, in a yarn twister, a ring traveller which reduces the strain and wear on the yarn and which also reduces the wear on the ring traveller during the twisting operation.

It is yet a further object of this invention to provide in a yarn twister a yarn guide in which the wear on the guide is substantially reduced during the yarn twisting operation.

In accordance with the present invention, the yarn guide has the structure of a bearing having inner and outer races and antifriction elements therebetween. The free rotation of the inner race, through which the yarn is guided, results in reduced wear over the inner surface of the inner face.

The lower section of the ring traveller, according to the present invention, is formed to embrace the inner periphery of the ring while permitting sliding of the ring traveller therealong. Disposed at the upper end of the ring traveller is a freely rotatable roller over which the yarn is guided on its way to the bobbin.

The advance of the yarn causes the roller to rotate thereby reducing the relative friction between the yarn and the traveller, and also reducing the strain on the yarn and the wear on the ring traveller.

This invention finds particular advantageous operation when used in twisting coated yarn. As both the yarn guide and ring traveller rotate along with the yarn, there is substantially no relative motion between the yarn, and the yarn guide and ring traveller. Resultingly, there will be virtually no removal of the coating from the yarn during the yarn twisting operation.

Further objects and features of the present invention will become apparent from the detailed specification below when studied in conjunction with the appended figures which form part of the application and in which:

5 FIG. 1 is a perspective view of a yarn guide and ring-and-traveller means of the invention;

FIG. 2 is an elevational view of the ring traveller according to the present invention;

10 FIG. 3 is an end view of the ring traveller of FIG. 2 as it appears from the left of FIG. 2;

FIG. 4 is a top plan view of the ring traveller of FIG. 2;

15 FIG. 5 is a top plan view of a yarn guide according to the present invention;

FIG. 6 is a cross section, taken along line 6—6 of FIG. 5;

FIG. 7 is an elevational view of a second embodiment of a ring traveller;

20 FIG. 8 is an end view of the ring traveller of FIG. 7 as it appears from the left of FIG. 7; and

FIG. 9 is a top plan view of the ring traveller of FIG. 7.

Referring now to FIG. 1, there is shown a typical rotary bobbin 1 having an upper circular end flange 2 and a lower circular end flange 3. A ring guide 4 coaxially surrounds the bobbin and is carried by an unillustrated rail.

Ring 4 has an inner circular peripheral flange 5 slidably embraced by the ring traveller 6 which is slidable therearound. A yarn guide 7 is fixedly disposed above and coaxial with the bobbin 1.

30 Yarn 8 is first passed through the passageway 9 within the guide 7 and then passes therefrom through the ring traveller 6. The yarn 8 is then wound onto the bobbin 1 by the rotational movement of bobbin 1 which causes the ring traveller 6 to move around the ring 4. The bobbin 1 is also moved axially with respect to the ring 4 so that the 35 yarn 8 builds a package on the bobbin.

FIGS. 2 through 4 illustrate a preferred embodiment of the ring traveller according to the present invention. As shown in the figures, the lower portion of the ring traveller 6 consists of an upper hook 10 and a lower hook 11 connected by a shank portion 12. The lower portion is formed in one integral piece and is made of a substance such as molded nylon or plastic. The hooks are shaped to firmly fit around and slide on the inner periphery of the ring 4 as shown in FIG. 1.

40 A bracket 13 is fixedly mounted on upper hook 10 by means of a pin 14. Bracket 13 has two upstanding spaced ears 15 and 16 oppositely disposed from one another. Through the upper section of each of the ears 15 and 16 extends a pin 17 upon which a roller 18 is mounted for free rotation. The roller is formed with a groove defined by two truncated conical surfaces 19 and 20 which are connected at their small ends by means of a cylindrical shaft 21, around which the yarn 8 passes in 45 a simple arc while advancing to the bobbin 1.

50 The bobbin 1 is rotated and axially displaced by motion producing means which are well known in the yarn winding art and are therefore not further shown or described in this application. The rotational movement of the bobbin pulls the ring traveller around the inner periphery of the ring 4. Because of the angular lag between the points of engagement of the yarn with the ring traveller and the bobbin, the roller 18 has an axis making an angle α with a straight line normal to a radial plane including the bobbin axis. Angle α may be in the range of 15°—45° and is preferably about 25°.

55 FIGURES 5 and 6 illustrate the basic construction of the ball bearing yarn guide 7. As shown in FIGS. 5 and 6, the ball bearing guide comprises an outer race 22 and an inner race 23. Extending directly from and integrally formed with outer race 22, is a mounting element or

extension 26, which is adapted to be mounted onto a bracket (not shown) to place the yarn guide in proper orientation with respect to the bobbin, as shown in FIG. 1. A passageway 9 is formed by inner race 23 to permit the passage of the yarn 8 therethrough during the twisting operation, as shown in FIG. 1.

Between races 22 and 23 are disposed antifriction elements formed by a series of balls 24, and the bearing is preferably of the self-aligning type. In accordance with this construction, when the yarn passes along the inner periphery 25 of the inner race 23 the force exerted by the yarn on the inner race 23 will cause the inner race 23 to rotate with respect to outer race 22, thereby reducing the wear on the surface 25 caused by the yarn during the twisting operation. Due to the rotation of the inner ring 23, the wear on surface 25 will be uniform, thereby insuring that the yarn will continue to be uniformly guided even after long usage of the guide 7.

FIGS. 7 through 9 illustrate yet another embodiment of a ring traveller embodying the inventive features of the present invention. With reference to these figures, a ring traveller 30 is shown having an upper hook portion 31, a lower hook portion 32 and a shank portion 33. The hook portions 31 and 32 and the shank portion 33 cooperate to firmly engage with and slide along the inner periphery of the ring 4 shown in FIG. 1. Extending rearward of the hook portions, to the left as shown in FIG. 7, and integrally formed with the shank portion 33 are triangular extensions 34 and 35, which form a yoke assembly. Each extension has a passageway formed therethrough, through which a pin 36 is placed for rotational movement. Upon pin 36, a roller 37 is rotatably mounted so that the pin and roller combination is free to rotate within the space between extensions 34 and 35.

During the yarn twisting operation the yarn is passed from above the ring traveller 30, around the roller 37, to extend to the left of the ring traveller as shown in FIG. 7. The yarn is then formed onto the bobbin as shown in FIG. 1. Roller 37 is formed with an arcuate cylindrical groove over which the yarn passes during the twisting operation. The yarn moving over the roller surface, causes the roller and pin to freely rotate therewith, so that there is virtually no friction between the yarn and the roller surface, nor is there relative motion between the yarn and the roller surface.

While I have described certain embodiments of my invention, I desire to have my invention not limited by the embodiments shown, but rather by the scope of the claims which are appended below.

What is claimed is:

1. In a yarn twister combination having a bobbin, yarn guide means spaced from and coaxial with said bobbin, a guide ring surrounding and spaced from said bobbin, and a ring traveller embracing said guide ring, the improvement comprising a yoke shape assembly attached at its closed end to said ring traveller, said assembly having a grooved roller rotatably mounted within the open end of said yoke and adapted to pass said yarn from said guide means to said bobbin through a simple arc.

2. The combination of claim 1, wherein said yarn guide means is parallel to and coaxial with said bobbin and has the construction of a bearing provided with an inner race through which the yarn moves, an outer race surrounding said inner race, and anti-friction elements between said races.

3. The combination of claim 1 and wherein said roller comprises oppositely directed coaxial truncated conical segments each having large and small ends and a cylindrical shaft interconnecting said small ends of said segments and defining said groove therewith.

4. The combination of claim 2, further comprising a mounting element integrally formed with and extending laterally from the outer race.

5. A combination as recited in claim 2 and wherein said bearing is a self-aligning ball bearing.

6. A yarn twister combination according to claim 1, wherein said yoke-shaped assembly comprises an upper hook and a lower hook connected by a shank portion, said yoke-shaped assembly being carried by said upper hook and having two spaced upstanding ears, said roller extending between and being rotatably carried by said ears.

7. The combination according to claim 1, wherein said yoke-shaped assembly comprises a pair of separated lateral extensions, and wherein said roller extends between and is rotatably carried by said extensions.

8. In a yarn twister combination, especially for coated yarn, having a bobbin, yarn guide means spaced from and coaxial with said bobbin, a guide ring surrounding and spaced from said bobbin, and a ring traveller embracing said guide ring, the improvement comprising a yoke-shaped assembly attached at its closed end to said ring traveller, said assembly having a grooved roller rotatably mounted within the open end of said yoke-shaped assembly and adapted to pass said yarn from said guide means to said bobbin through a simple arc, said roller having an axis defining with a straight line normal to a radial plane, which includes the bobbin axis, an angle of between 15° and 45°.

9. The combination of claim 8 and wherein said angle is approximately 25°.
